UNITED STATES PATENT OFFICE.

JOSEPH W. BETTENDORF, OF BETTENDORF, IOWA.

PROCESS OF MAKING JOURNAL-BOX LIDS.

Original application filed August 23, 1926, Serial No. 130,845. Divided and this application filed December 2, 1926, Serial No. 152,145.

This invention relates to journal box lids and more particularly to the process of making them from a single sheet or plate of metal.

- 5 An object of this invention is to provide a journal box lid which can be readily made from a plate of metal with an integral pintle pin to cooperate with standard journal box hinge lugs.
- 10 A further object of this invention is to provide a simple and efficient process for the manufacture of such a journal box lid in which the integral pintle pin, the connecting straps and the side flanges can be 15 formed by shaping a single metal sheet or plate.

These and other objects of my invention will be apparent from the following description and annexed drawings, in which

- 20 Figure 1 is a front elevation of the blank from which one of the forms of my journal box lid may be formed.

Fig. 2 is a side elevation of the blank shown in Fig. 1.

- 25 Fig. 3 is a front elevation of the lid completely formed from the blank in Fig. 1.

Fig. 4 is a side elevation of Fig. 3.

Fig. 5 is a section on line 5—5 of Fig. 3.

- 30 Fig. 6 is a front elevation of a modified form of blank.

Fig. 7 is a side elevation of the blank shown in Fig. 6.

Fig. 8 is a front elevation of the lid formed from the blank shown in Fig. 6.

- 35 Figs. 9, 10 and 11 are taken on the lines 9—9, 10—10 and 11—11 of Fig. 8.

The blank shown in Fig. 1 from which the journal box lid is to be formed comprises a body portion 1 with an aperture 2 formed 40 near its upper margin. At the sides of the aperture 2 are the members 3 which form the straps connecting the member 4 therewith. Wings 5 are provided which extend from the metal forming the member 4.

- 45 Projecting from the lower part of the body portion is the finger piece 6 which is provided for readily opening and closing the lid as is well understood.

The metal surrounding the body portion of the blank along the sides, the bottom and 50 portions of the top is provided to form the side flanges 1^b of the lid to engage the sides, bottom and a portion of the top of the journal box (not shown) and fit therewith to substantially exclude the dust and dirt from 55 obtaining access to the box.

After the blank shown in Fig. 1 is formed from a single plate or sheet of metal it is then subjected to a pressing operation which turns down the flanges 1^b and offsets the 60 finger piece 6 from the body of the metal plate as well as offsetting the connecting strips 3 therefrom. The metal 4 is rolled to form the pintle as shown in Fig. 3 and the extension wings 5 at the same time are 65 turned back and pressed against the connecting strips 3 and in the form of the invention shown in Figs. 1 to 5 are pressed to overlie and engage the face of the body portion of the lid along its upper edge. The 70 portion 5^a of the extension wings thus reinforces the connecting straps and makes them considerably more rigid and may even be subsequently spot welded to the upper marginal portion of the journal box lid and 75 to the straps, if desired.

The body portion of the journal box lid may be stiffened by suitable stiffening depressions 7, 8 and 9 formed therein by pressing, as is well understood.

In the modified form of journal box lid shown in Figs. 6 to 11, the construction is similar to that shown in Figs. 1 to 5, with the exception that the body portion 15 of the blank is shorter than the blank shown in Fig. 1 because the portion 16 of the blank which is rolled to form the integral pintle 17 has no extensions or wings.

The blank 15 is provided with an aperture 18 near its upper margin to receive a portion of the journal box hinge lug (not shown), and the portion 16 is connected by the straps 19 to the body portion of the blank.

Surrounding the bottom, sides and a portion of the top of the blank, metal is pro-

vided to form turned-in side flanges 15^b to engage the sides, bottom and a portion of the top of the journal box to form a substantially tight joint therewith and exclude 5 the dust and dirt from the journal box.

The body portion 15 may be reinforced with depressions 20, similar to the depressions shown in Fig. 3 and be provided with a similar finger piece 21.

10 The metal of the portion 16 is rolled to form the integral pinte 17 and the edge of the metal 16 abuts the lower part of the pinte, as shown in Fig. 11, so that a substantially hollow, cylindrical pinte is 15 formed without the protrusion of a free edge.

The connecting straps 19 which connect the portion 16 with the body portion 15 of the blank may have suitable ribs or flutes 20 22 pressed therein to make them more rigid. In this form of construction it will be seen that less metal is used to form the journal box lid as the blank required is shorter because of the omission of the wings or extensions 25 shown in the form of Fig. 1.

It will thus be seen that I have provided a process for the manufacture from sheet or plate metal of journal box lids with integral pinte adapted to cooperate with journal box 30 hinge lugs of the usual construction as set forth in my copending application Serial No. 130,845, filed August 23, 1926, of which application this is a division.

Furthermore, it is to be understood that 35 the particular forms of apparatus shown and described, and the particular procedure set forth, are presented for purposes of explanation and illustration and that various modifications of said apparatus and procedure can be made without departing from 40 my invention as defined in the appended claims.

What I claim is:

1. The method of making a journal box 45 lid, comprising cutting from a single metal plate a suitable metal blank provided with connecting straps and a strip of metal joining the straps, rolling the strip of metal to form a hollow, cylindrical pinte spaced from the body portion of the blank by said straps, and reinforcing the straps and body portion of the lid.

2. The method of making a journal box 55 lid, comprising cutting from a single metal plate a suitable metal blank provided with connecting straps and a strip of metal joining the straps, rolling the strip of metal to form a hollow, cylindrical pinte spaced from the body portion of the blank by said straps, forming integral reinforcing members in the body portion of the blank, and reinforcing the connecting straps.

3. The method of making a journal box 60 lid, comprising cutting from a single metal plate a suitable metal blank provided with

connecting straps and a strip of metal joining the straps, rolling the strip of metal to form a hollow, cylindrical pinte spaced from the body portion of the blank by said straps, turning down portions of the top, 70 sides and bottom of the blank to form integral side flanges on the lid, and suitably reinforcing the connecting straps.

4. The method of making a journal box lid, comprising cutting from a single metal 75 plate a suitable metal blank provided with connecting straps and a strip of metal joining the straps, rolling the strip of metal to form a hollow, cylindrical pinte spaced from the body portion of the blank by said 80 straps, forming integral reinforcing members in the body portion of the blank, reinforcing the connecting straps, and offsetting the pinte and connecting straps from the plane of the body portion of the lid. 85

5. The method of making a journal box lid, comprising cutting from a single metal plate a suitable metal blank having connecting straps and a strip of metal joining the 90 straps, rolling said strip of metal to form a hollow cylindrical pinte spaced from the body portion of the blank by said straps and offsetting the straps and pinte from the body portion of the lid.

6. The method of making a journal box 95 lid, comprising cutting from a single metal plate a suitable metal blank having a finger piece and provided with connecting straps and a strip of metal joining the straps, rolling said strip of metal to form a hollow, 100 cylindrical pinte spaced from the body portion of the blank by said straps, and offsetting the finger piece, the straps and the pinte from the body portion of the lid.

7. The method of making a journal box 105 lid, comprising cutting from a single metal plate a suitable metal blank having a finger piece and provided with connecting straps and a strip of metal joining the straps, rolling said strip of metal to form a hollow, 110 cylindrical pinte spaced from the body portion of the blank by said straps, turning down portions of the sides, bottom and top of the blank to form side flanges, and offsetting the finger piece, the straps and the pinte from the body portion of the lid. 115

8. The method of making a journal box lid, comprising cutting from a single metal plate a suitable metal blank having a finger piece and provided with connecting straps 120 and a strip of metal joining the straps, rolling said strip of metal to form a hollow, cylindrical pinte spaced from the body portion of the blank by said straps, turning down portions of the sides, bottom and top 125 of the blank to form side flanges, and reinforcing the connecting straps and body portion of the lid.

9. The method of forming a metal closure member or the like with an integral hinge 130

pintle which comprises cutting from a single metal plate a suitable metal blank having connecting straps projecting from the body thereof and a strip of metal joining 5 the straps and extensions projecting beyond said strip of metal, rolling said strip of metal to form a hollow cylindrical pintle

extending across the space between the straps and spaced from the body portion by said straps, and bending back said extensions to overlie and reinforce said connecting straps. ¹⁰

In testimony whereof I affix my signature.
JOSEPH W. BETTENDORF.
